DESIGN FOR A SUPPORTING LEG FOR A TABLE OR SIMILAR ARTICLE

Maurice H. Levine, Chicago, Ill.

Application January 22, 1940, Serial No. 89,632

Term of patent 3½ years

To all whom it may concern:

Be it known that I, Maurice H. Levine, a citizen of the United States, residing at Chicago, in the county of Cook and State of Illinois, have invented a new, original, and ornamental Design for a Supporting Leg for a Table or Similar Article, of which the following is a specification, reference being had to the accompanying drawing, forming part thereof.

Fig. 1 is a perspective view of a supporting leg for a table or similar article showing my design.

Fig. 2 is a front elevational view of same.

Fig. 3 is a sectional view taken on line 3—3 of Fig. 2.

I claim:

The ornamental design for a supporting leg for a table or similar article, as shown.

MAURICE H. LEVINE.
